UNITED STATES PATENT OFFICE.

EMANUEL A. SPEEGLE, OF SAWTELLE, CALIFORNIA.

CURRENT-MOTOR.

1,131,617.

Specification of Letters Patent.

Patented Mar. 9, 1915.

Application filed September 2, 1913. Serial No. 787,695.

To all whom it may concern:

Be it known that I, EMANUEL A. SPEEGLE, a citizen of the United States, residing at Sawtelle, in the county of Los Angeles, 5 State of California, have invented new and useful Improvements in Current-Motors, of which the following is a specification.

This invention relates to current motors, and the principal object is to provide a current 10 motor with feathering blades.

It is also an object to provide a current motor with blade frames which form sufficient engagement with the supporting means to turn the latter.

15 It is a further object to provide a current motor with an articulated blade, one of which members is fixed and secured to a triangularly formed frame acting as the teeth on an endless belt or chain.

20 In the drawings accompanying this specification and forming herewith the application for Letters Patent: Figure 1 is a longitudinal vertical section through a float showing the invention applied thereto. Fig.

25 2 is a transverse section on the line 2—2 of Fig. 1, viewed in the direction indicated by the arrows. Fig. 3 is a detail perspective view of the blade supporting means with a blade secured thereto.

30 More specifically in the drawings, 5 designates a float or scow, preferably of the divided form shown, or having a well formed therein transversely of whose longitudinal walls are journaled a pair of shafts 7 and 8 35 which are spaced the desired distance to accommodate the movable blade carrying member and preferably with the journals 9 thereof placed in the side walls of the well 6 above the water line 10.

40 Mounted upon the shafts are the frames 11 and 12 which are preferably formed of metallic disks which are keyed to the shafts and provide support for a plurality of radially disposed arms or spokes 14, these spokes 45 being preferably grooved in annular relation to one another and are adapted to carry in the grooves the wire connecting or chain links 15 which join the frames 17 to form a continuous belt or chain supported between 50 a pair of registering wheel members spaced apart upon the respective axles.

The blade supporting member 17 is preferably formed of strap metal formed in the triangular configuration shown and 55 joined or welded to form the blade supporting face 18, together with the section

19 adapted to have formed thereupon the eyes or staples 20 to which the links 15 are secured. A pair of these triangular blade members make up the blade unit and are 60 connected by means of a board 21 secured to the parallel faces of the two members by the fastenings 22, the board being of such width that the links 15 and the plates 18 will register with the spokes of the spaced 65 wheels and the links 15 will be in the grooves in the ends of the arms 14.

Secured to the outer edge of the board 21 forming the blade or the edge adjacent the face 14 of the blade support is hinged a second board to form a blade 23, two hinges 25 connecting the two, and to limit the movement of this blade straps 26 are secured to a spacing bar 27 connecting the oppositely disposed ends of the face 19 so that 75 when the blades are immersed in the water, as shown in Figs. 2 and 3, the blades 23 will assume a vertical position in the water while the blade portion 21 will be inclined slightly from the vertical so that a dish or 80 cup effect is presented to the current flowing as indicated by the arrows 28.

The shaft 7 is shown as disposed in the forward end of the float or that end disposed in the direction as opposed to the flow 85 of the current in which the float is anchored, is preferably provided with a pinion 29 which is keyed to the shaft 7 and adapted to carry a chain 30 which leads up to the platform or deck upon which is mounted the 90 air compressor 32. This air compressor is provided with a shaft 33 carrying a pinion 34 over which the chain 30 is carried and movement of the shaft 7 is effected by the current acting upon the blades which will 95 revolve the shaft 33 and air is stored up and carried to any suitable tank for storage to perform useful work.

Any other mechanism may be connected directly to the shafts so that the energy ordinarily wasted by the movement of currents of water will be conserved and turned to beneficial results.

What I claim is:

1. A current motor, comprising a float 105 having a longitudinally disposed well therein, transversely mounted shafts in said well, grooved radial arms disposed on said shafts, a belt engaging said arms adapted to be supported thereon in movable engagement, 110 a plurality of blade carrying members carried on said belt adapted to engage said

arms and extend therebetween, blades rigidly carried thereby arranged at an inclination to the belt on the inner side thereof, and blades hinged to the first-named blades on the opposite side of the belt in relation to said first-named blades, said hinged blades having limited movement in relation to the belt.

2. A current motor, comprising a floating member, revoluble means to support an endless belt thereon, triangular arms supported on said belt adapted to engage and revolve said supporting means, blade members se-

cured to said triangular arms, hinged blades secured to said first mentioned blades, and means to limit the movement of said hinged blades, whereby a revoluble structure is provided to receive the impact of the current flowing by said floating member.

In witness that I claim the foregoing I have hereunto subscribed my name this 20th day of August, 1913.

EMANUEL A. SPEEGLE.
